Primary Examiner — Jonathan J Han*Assistant Examiner* — Caitlin Mackenzie Williams(74) *Attorney, Agent, or Firm* — Collard & Roe, P.C.(57) **CLAIM**

The ornamental design for a shoe as shown and described.

DESCRIPTION

The patent or application file contains at least one drawing executed in color. Copies of this patent or patent application publication with color drawing(s) will be provided by the Office upon request and payment of the necessary fee.

The sole FIGURE is a top view of a shoe, showing my new design.

The dash-dot lines indicate the boundary of the claimed design and form no part of the design itself. The portions of the shoe outside the dash-dot boundary lines, which are shown in white and bounded by the broken lines, form no part of the claimed design.
